UNITED STATES PATENT OFFICE.

JACUB SCHWARTZMAN, OF BROOKLYN, NEW YORK.

WIRE FABRIC.

1,141,418.

Specification of Letters Patent. Patented June 1, 1915.

Application filed June 24, 1913. Serial No. 775,478.

To all whom it may concern:

Be it known that I, JACUB SCHWARTZMAN, a citizen of the United States, residing at Brooklyn, in the county of Kings and State of New York, have invented certain new and useful Improvements in Wire Fabrics, of which the following is a specification.

This invention relates to wire or metallic fabrics, the object of the invention being to provide an improved fabric of this character particularly adapted for use in connection with spring mattresses and which will be simple in construction, durable in use, and comparatively inexpensive to manufacture, made up of links quickly and inexpensively assembled, and in which the pull on the several links of the fabric will be in a straight direction lengthwise of the fabric, while at the same time the fabric will be unusually 20 resilient owing to the peculiar construction of the links.

A further object of the invention is the provision of an improved link for the body of the fabric.

25 A further object of the invention is the provision of an improved edge-forming link. In the drawings accompanying and forming part of this specification, Figure 1 is a plan view of this improved fabric having one edge thereof provided with the improved edge-forming links; Fig. 2 is a detail view, full size, of one of the improved links for the body of the fabric; Fig. 3 is an edge view of the link shown in Fig. 2; Fig. 4 is a view, full size, of one of the improved edge-forming links; Fig. 5 is an edge view of the link shown in Fig. 4; Fig. 6 is a detail view illustrating a pair of the links shown in Fig. 2 assembled; and Fig. 7 is a 40 view illustrating another way of assembling the same form of links.

Similar characters of reference indicate corresponding parts throughout the several figures of the drawings.

45 The fabric is made up of a series of interconnected links or units 2, each comprising a pair of relatively straight portions 3 and 4, running in substantial parallelism with each other and connected by an inclined or diagonal portion 5 and thus forming a link having very close resemblance to a capital letter "N". Each straight portion of the links 3 and 4 terminates in hooks 3' and 4' respectively, and each straight portion in the form shown in Fig. 2 is connected with the diagonal or inclined portion 5 by out-

wardly extending or laterally deflected angular portions 6 and 7, which angular portions are for the purpose of interlocking or connecting one link with its companion link in the manner shown at 9, which illustrates the parts twisted as it were together, although this twist, as will be obvious, results because of the formation of the links at the points 6 and 7 in the manner shown and described. In forming the angular portions 6 and 7, it will be observed that they are so bent that the portion 6 will be inclined or extend to one side of the plane of the link, (see for instance the edge view in Fig. 3), being connected with the portion 7 by a short upright bend 8, which permits it together with the deflected formation of this portion of the link to be interconnected in the manner shown at 9. Each link thus has 75 a pair of what may be considered as twisted parts or wires.

The fabric is thus made up of a series of N-shaped units which are connected together, thus forming lengthwise extending 80 rows of interlocked links, this connection being an interlocking one in all of the forms except that shown in Fig. 7, in which each pair of N-shaped units are connected by a ring. For reinforcing and strengthening 85 the edge, the link shown in Fig. 4 may be used although this is not absolutely essential, as instead of using such a link a metal strip attached at its ends to the usual cross angle bars to which the helical springs are 90 connected may be interwoven with the outer diagonal portions 5 along the edge of the fabric if preferred.

When the several units or links have been assembled in the manner shown they may 95 be connected to the cross angle bars 10 by suitable helical springs 11 for which purpose the ends of the several units may have connected therewith rings 12. When, however, the edge links 13 shown in Fig. 4 are used, connecting links similar to that shown at 14 may be used to which the helical springs 15 may be attached. These edge-forming links 13 each comprise likewise a pair of lengthwise extending portions 16 each terminating in a hook 17 and which straight portions are connected by triangular formed portions 18 and 19, the triangular portion of which is formed in much the same way as portion 8, that is to say the parts 18 and 19 are connected by an offset portion 21, shown more clearly in Fig. 5.

In Fig. 7 instead of the N-shaped units being connected by interlocking directly, for instance in the manner shown at 9 in Fig. 6, they are connected by means of a ring 22, which however is interlocked with the twisted units of the links.

It will be observed that by means of the present improvement the pull on the links is in a straight direction lengthwise thereof and on the straight portions 3 and 4 thereof, and it will also be observed that the helical springs may be attached at the terminus of each straight portion, that is to say at the point where the hook 3' or 4' is formed according to the way that the links are assembled, and at the point where the loop 6' or 7' is formed. When the links are assembled in the manner shown in Fig. 1 the helical spring is connected to a link at the hook portion 3' and to a pair of the same links at the interlocked loop portions 6'.

Thus it will be observed that both ends of the fabric are formed, and connected alike, for the connection of the helical springs, that is to say the fabric by being formed in the manner shown does not have hooked ends at one end of the fabric for connection of the helical springs and looped ends at the other end, that is it does not have one formation at one end of the fabric and a different formation at the other. On the contrary the ends of the fabric at both ends thereof are similarly formed for the connection of the helical springs or any other form of connection that may be desired to be used.

When the loop portion 6' or 7' (see Fig. 2), comes at the outer edge of the fabric a connecting member similar to that shown at 25 (see Fig. 1) may be used in connection with a helical spring.

In practice the several N-shaped units are assembled in rows in the manner shown in Fig. 1.

The projecting or bulged portions formed by the laterally deflected parts 6 and 7, together with the offset portion 8 at the juncture of such portions 6 and 7, materially increase the resiliency of the links or units, which resiliency is also very much assisted by the N-shaped formation of the links while at the same time a straight pull by reason of the straight parallel portions each terminating in a hook or loop is obtained and maintained.

55 I claim as my invention:

1. A metal fabric for bed springs comprising a multiplicity of wire units arranged in rows, each unit consisting of a pair of parallel straight portions connected by an inclined portion and having intermediate the juncture points of such inclined part and the ends of such straight portions laterally deflected angular portions, each such angular portion having an offset portion.

60 2. A metal fabric for bed springs comprising a multiplicity of wire units arranged in rows, each unit consisting of a pair of parallel straight portions connected by an inclined portion and having intermediate the juncture points of such inclined part and the ends of such straight portions laterally deflected angular portions, each such angular portion having an offset portion.

65 3. A metal fabric for bed springs comprising a multiplicity of wire units arranged in rows, each unit consisting of a pair of parallel straight portions connected by an inclined portion and having intermediate the juncture points of such inclined part and the ends of such straight portions laterally deflected angular portions, each such angular portion having an offset portion, and each straight portion terminating in a hook or loop.

70 4. A metal fabric for bed springs comprising a multiplicity of wire units arranged in rows, each unit consisting of a pair of parallel straight portions connected by an inclined portion, each of said straight portions terminating at its end in a loop or hook and at its opposite end in a bulged formed portion having an offset.

75 5. A metal fabric for bed springs comprising a multiplicity of wire units arranged in rows, each unit consisting of a pair of parallel straight portions connected by an inclined portion, extending from a point adjacent to one end of one straight portion to a point adjacent to the opposite end of the other straight portion, each of said straight portions terminating at one end in a loop or hook and interconnecting said end and its point of connection with the inclined portion in an offset portion.

80 6. A metal fabric for bed springs comprising a multiplicity of wire units arranged in rows, each unit consisting of a pair of parallel straight portions connected by an inclined portion, each of said straight portions terminating at one end in a loop or hook and at its opposite end in a bulged formed portion having an offset.

85 7. A metal fabric for bed springs comprising a multiplicity of wire units arranged in rows, each unit consisting of a pair of parallel straight portions connected by an inclined portion, each of said straight portions terminating at one end in a loop or hook and interconnecting said end and its point of connection with the inclined portion in an offset portion.

90 8. A metal fabric for bed springs comprising a multiplicity of wire units arranged in rows, each of the body rows consisting of N-shaped links interlocked.

95 9. A metal fabric for bed springs comprising a multiplicity of wire units arranged in rows, each of the body rows consisting of N-shaped links interlocked, said fabric having along its edges a series of links connected with the N-shaped links and of a different form therefrom.

100 10. A metal fabric for bed springs comprising a multiplicity of wire units arranged in rows, each unit consisting of a pair of parallel straight portions, each straight portion terminating in a hook or loop and each straight portion having intermediate its ends a projecting portion having an offset, said projecting portion comprising a laterally deflected angular portion located at the extreme end of its straight portion.

105 11. A metal fabric for bed springs comprising a multiplicity of wire units arranged in rows, each body unit consisting of a pair of parallel straight portions, each straight portion terminating in a hook or loop and each straight portion having intermediate its ends a projecting portion having an offset, said projecting portion comprising a laterally deflected angular portion located at the extreme end of its straight portion.

110 12. A metal fabric for bed springs comprising a multiplicity of wire units arranged in rows, each body unit consisting of a pair of parallel straight portions, each straight portion terminating in a hook or loop and each straight portion having intermediate its ends a projecting portion having an offset, said projecting portion comprising a laterally deflected angular portion located at the extreme end of its straight portion.

115 13. A metal fabric for bed springs comprising a multiplicity of wire units arranged in rows, each body unit consisting of a pair of parallel straight portions, each straight portion terminating in a hook or loop and each straight portion having intermediate its ends a projecting portion having an offset, said projecting portion comprising a laterally deflected angular portion located at the extreme end of its straight portion.

120 14. A metal fabric for bed springs comprising a multiplicity of wire units arranged in rows, each body unit consisting of a pair of parallel straight portions, each straight portion terminating in a hook or loop and each straight portion having intermediate its ends a projecting portion having an offset, said projecting portion comprising a laterally deflected angular portion located at the extreme end of its straight portion.

125 15. A metal fabric for bed springs comprising a multiplicity of wire units arranged in rows, each body unit consisting of a pair of parallel straight portions, each straight portion terminating in a hook or loop and each straight portion having intermediate its ends a projecting portion having an offset, said projecting portion comprising a laterally deflected angular portion located at the extreme end of its straight portion.

- of a pair of parallel straight portions each terminating in a hook or loop and having intermediate its ends a projecting portion having an offset, the offset of one link being interlocked with that of another, and said straight portions connected by an inclined portion, and a multiplicity of side links interlocked with an outer row of the body links.
- 10 10. A link for a metal fabric comprising an N-shaped member, consisting of a pair of parallel straight portions connected by an inclined portion, each of said straight portions terminating at one end in a loop

or hook and having intermediate said end 15 and its point of connection with the inclined portion a projecting portion having an offset portion.

11. A link for a metal fabric comprising an N-shaped member consisting of a pair 20 of parallel straight members connected by an inclined portion, each of said straight members having an offset portion.
